(57) **CLAIM**

The ornamental design for an exhaust guard, as shown and described.

DESCRIPTION

FIG. 1 is a front right perspective view of an exhaust guard, showing my new design;

FIG. 2 is a left side elevation view thereof;

FIG. 3 is a rear elevation view thereof; and,

FIG. 4 is front elevation view thereof.

The broken lines in the figures show portions of the exhaust guard which form no part of the claimed design.
